Application May 4, 1934, Serial No. 723,850

13 Claims. (Cl. 101—212)

This invention relates to printing presses and a primary object thereof is to provide an improved construction of press capable of printing on a web a series of immediately adjacent impressions, the length of which may vary in accordance with the adjustment of the press. Our invention is here embodied in a press of the type wherein a printing cylinder is reciprocated along the web, rolling in contact with the paper to make an impression thereon.

Our invention will be well understood by reference to the following description of the specific embodiment shown by way of example in the accompanying drawings, wherein:—

Fig. 1 is a side elevation of a portion of a press; Fig. 2 is a broken side elevation of a smaller scale showing parts of the press located to the right of Fig. 1. A portion of the right of Fig. 1 duplicates a portion of the left of Fig. 2 to show the relation.

Fig. 3 is a transverse section with parts broken away illustrating the impression bed and appurtenant mechanism;

Fig. 4 is a plan view showing the impression cylinder and appurtenant mechanism, various parts being omitted for simplicity;

Fig. 5 is a section on line 5—5 of Fig. 4 on a larger scale;

Fig. 6 is a section on line 6—6 of Fig. 5;

Fig. 7 is a section on line 7—7 of Fig. 4 on a larger scale and with parts broken away;

Figs. 8, 9 and 10 are sections on the like numbered lines of Fig. 7 respectively;

Fig. 11 is a partly diagrammatic side view illustrating inking mechanism;

Figs. 12 and 13 are comparable fragmentary views illustrating different positions of the parts;

Fig. 14 is a detail in plan of part of the mechanism of Fig. 11 in the position of that figure;

Fig. 15 is a detail end view of elements appearing in Fig. 11.

Referring to the drawings, and more particularly to Figs. 1, 2 and 3, the press there shown is organized on a pair of longitudinally extending main frames 20. A power shaft 22 shown at the left of Fig. 1 and driven through the band wheel 24 from any suitable source of power actuates various constituent mechanisms of the press, in part through the longitudinally extending shaft 26. Between the side frames 20 (see Fig. 3) we provide a suitable impression surface or table 28. As seen in Fig. 1, the web of paper *w* may be drawn from any suitable supply and herein is drawn forwardly continuously but at a variable

rate by unwinding rolls 30 driven through an adjustable disc and roller train 32 from the main shaft and passes over a floating loop or dance roll 34 to the table or impression surface 28. It is drawn intermittently over the table by means of feed rolls disposed to the right beyond Fig. 1. These rolls are not illustrated as such but their position is indicated in Fig. 2 wherein is shown the driving mechanism therefor through a suitable intermittent actuating device such as the ratchet wheel 36 adapted to be rotated in one direction and in one phase of the movement of gear 38 which is oscillated by rack 40 reciprocated from a crank disc 42 taking motion from the shaft 26, as indicated in Fig. 2.

On the side frames 20 is supported in opposition to the table 28 a reciprocating frame or carriage 48 carrying one or more printing cylinders 50. We have herein illustrated two such cylinders, the press being adapted to print in two colors. The carriage is reciprocated longitudinally of the frames by means of connecting rods 52 secured thereto at either side thereof and crank driven through wheels 54 taking motion from power shaft 22. To permit substantially the full circumference of the cylinders 50 to be utilized, when desired, for printing, the length of stroke of the carriage 48 is herein equal to the circumference of the cylinders. As the carriage is reciprocated over the impression bed 28 the cylinders are positively rotated by means hereinafter to be described.

In the embodiment of the invention shown the cylinders print while the carriage 48 is moving from right to left viewing Fig. 1 and make no impression during the opposite phase of the reciprocation. Herein the axes of the cylinders move in a single horizontal plane and the impression surface 28 is tripped or lowered out of cooperation with the cylinders during the return movement of the carriage from left to right viewing Fig. 1. The mechanism herein illustrated for effecting this is best seen in Fig. 3. The table 28 is supported by suitable vertical screw shafts 56 working in nuts 58 rotatably mounted in standards 60. The nuts are formed externally with gear teeth meshing with racks 62 which also have upwardly facing rack teeth meshing with sectors 64 on rock shaft 65 controlled by cams 66 on a cam shaft 68 driven through gear train 70 and countershaft 72 from the longitudinally extending shaft 26. The left-hand cam viewing Fig. 3 is a track cam and the right-hand cam an edge cam. It will be understood that at the extremes of movement of the carriage 48 the racks 55

- 62 are reciprocated through the oscillation of the sectors under control of the cams and turn the nuts 58 slightly, causing the screws 56 to lower or elevate the table 28 respectively to a position 5 wherein the paper 28 will be moved away from the path of the printing plate on the surface of the printing cylinder 50 or to an elevation wherein the paper makes contact with such plate to receive an impression therefrom.
- 10 An important feature of the press herein shown is found in the fact that the printing cylinder 50 rotates in the same direction during both phases of movement of the carriage 48 in which it is rotatably mounted. This is important particularly in insuring proper application of ink to the plates. Rotation of the cylinder is herein effected by means of fixed racks 74 and 76 in which run pinions 78 and 80 respectively connected to the cylinder in such a way as to drive the same in 15 desired manner as presently to be described. Since in the embodiment of the invention shown the cylinder moves with its axis in a fixed horizontal plane and the pinions rotate about this axis, as will appear, and the racks are fixed, the 20 construction is an example of a mechanism in which the rack and pinion means are at fixed positions relative to the cylinder. Hence the toothed parts cooperate along unvarying predetermined pitch lines ensuring an easy and accurate movement.
- 25 As best seen in Figs. 7 to 10, the pinions 78 and 80 are loosely mounted on the shaft 82 of the printing cylinder 50. The racks 74 and 76 oppose each other, engaging their pinions at opposite sides of the axis so that one pinion is driven in opposite direction to the other, the direction of movement of each pinion, of course, reversing as the direction of movement of the carriage changes from one phase of its reciprocation to another. In Fig. 7 we may consider the carriage as having completed its stroke toward the right and just about to start back toward the left on its printing stroke and the pinions 78 and 80 respectively about to be revolved 30 in the direction of the arrows shown by the racks meshing therewith. Suitable oppositely arranged one-way clutch mechanisms are interposed between the pinions and the cylinder. Thus, when the carriage starts to move to the left, pinion 78 35 will begin to rotate clockwise and (see Fig. 8) the square openings 84 therein will ride over the bevelled ends of the axially disposed spring-pressed dogs 86 carried by the adjacent disc 88 which is fast on the shaft 82 and will be ineffective to drive this disc and the cylinder. On the contrary pinion 80 (see Fig. 9) has completed a clockwise rotation which carried the leading walls of square openings 90 therein over the bevelled faces of dogs 92 permitting the dogs to snap into the openings with the shoulders thereof in position as seen in Fig. 9 to permit pinion 80, now about to move counterclockwise or in the direction of the arrow in Fig. 9, to drive the disc 94 which carries the dogs in a counterclockwise direction and therewith the cylinder 50 to the shaft 82 of which the disc is keyed. On the ensuing opposite phase of the reciprocation of the cylinder carriage the two pinions will be moving in the opposite directions, the clutch provided by dogs 92 will slip while the clutch provided by dogs 86 will drive, but since the direction of motion of pinion 78 will have been reversed because it will be travelling in the opposite direction along its rack, pinion 78 will then be moving counter-

clockwise and will drive the cylinder counterclockwise. The cylinder thus rotates constantly in one direction.

To prevent overthrow of the cylinder at the extremes of movement when the drive changes from one pinion to the other suitable means may be provided for braking its rotary motion at such extremes of movement. The construction here illustrated will be best understood by Figs. 4, 5 and 6 wherein one end of shaft 82 of the cylinder is shown as carrying a brake drum 96 with which cooperate two substantially semi-circular brake shoes 98 pivoted at 100 on the side frame of the carriage 48. The shoes 98 are normally pressed apart and out of braking contact with drum 96 by a spring 102 between their free ends. The spring may surround the bolt 104 connecting the free ends of the brake shoes, which bolt is pivoted on the end of shaft 106 journalled in one of the side frames of the carriage 48. To apply the brake shoes against the force of the spring the shaft 106 may carry an eccentric 108 adapted to engage the end of the lower brake shoe as indicated and shaft 106 may be rocked at the proper time by a lever 110 carrying the cam roll 112 co- 20 operating with rise 114 (see Fig. 4) adjustably secured on disc 116 mounted on and rotating with the shaft 82.

Suitable ink-applying rolls denoted generally by the numeral 118 (see Fig. 11) cooperate with plate cylinder 115 to apply ink thereto. We prefer, however, not to carry the entire inking mechanism on the carriage 48 but to provide stationary fountains 120 (see Fig. 1) on the main frame of the machine at either end of the path of movement of the carriage 48. From these fountains a ductor roll 122 may transfer ink to a distributing plate 124 from which in turn, preferably after the ink has been worked thereon by transversely vibrating distributor roll 126, a ductor roll 40 128 transfers it to the ink-applying rolls. To effect this purpose the ink-distributing plate (see Fig. 15) may be reciprocated relatively to carriage 48. Herein, as best seen in Fig. 11, there are two distributing plates 124, one for each cylinder 45 50, supported (see Fig. 15) through laterally extending arms 129 from the side members 130 slideable in ways in the side frames of carriage 48. The central portions of these members are provided with rack teeth 132 and the plates are reciprocated by the action of oscillating pinions 134 meshing with these teeth. The method by which these pinions are driven will be best understood from Figs. 1 and 4 and it will be seen that their common shaft 135 carries a pinion 136 55 which is oscillated by rack 138 driven by crank pin 140 on a gear 142 which runs in the rack 74. The timing of the parts is preferably such that the plate moves through several and preferably an odd number of cycles for each cycle of the carriage 48 for reasons which will appear.

On the extreme of the stroke of the carriage to the right as indicated in Fig. 11, the plate 124 from which ink is supplied to the adjacent plate cylinder (that shown in the figure) is protracted 65 from the frame 48 beneath ductor roll 122 which is operated by a suitably timed cam 146 (see Fig. 1) to transfer ink from the fountain to the plate. As the carriage then moves toward the left, the plate 124 is retracted beneath distributing roll 70 126 to a position beneath ductor roll 128. The side member 130 which supports the plates may carry cam surfaces 148 which cooperate with arms 150 operating ductor roll 128 in such manner that as the plate moves from the position of 75

Fig. 11 to the position of Fig. 12 the ductor roll 128 is lowered onto the plate to take ink therefrom. The carriage still moving toward the left, on account of the timing of the parts the plate 5 is again reciprocated to the right to the position of Fig. 13 causing the ductor roll to be lifted to transfer ink to the ink-applying rolls.

The ink-distributing plates 124 herein are moved through an odd number of strokes for 10 each stroke of the cylinder-carrying carriage 48, for example three strokes during each stroke of the carriage. This provides that the right-hand plate viewing Fig. 11 will be protracted into cooperation with the right-hand fountain when 15 the carriage is at its right-hand extreme of movement as illustrated and that the left-hand plate will be protracted into cooperation with the left-hand fountain when the carriage has moved to its extreme left-hand position. The fact that the 20 plates make more than one stroke during each stroke of the carriage provides for the operation of mechanism to transfer the ink as above described.

We have deemed it unnecessary to show in detail mechanism for operating all the rolls of the inking mechanism. Those carried by the carriage 48 may be driven through suitable trains from gear 152 (Fig. 4) on the cylinder shaft.

It will be understood that the length of the impression made on each cycle depends on the 30 length of the printing plate carried by cylinder 58 and that a length equal to the maximum length of plate which can be accommodated on the cylinder can be printed. The web feeding mechanism indicated in Fig. 2 is adjusted to draw forward during the idle stroke of the cylinder a sufficient length of web to provide for desired spacing of the impressions, usually such as to cause them immediately to succeed one another with no substantial intervening unprinted portions. 40 In the case of multi-color work the table 28 presents separate spaced impression surfaces to each cylinder 58 and the multi-color impression is completed by successive cycles. The maximum length of impression corresponds to the distance 45 between the centers of the cylinders. To cite an actual example, a two color press has been constructed having cylinders of 22-inch circumference spaced eighteen inches apart and is adapted to print on each cycle an impression varying from three to eighteen inches in length. The cylinders operate accurately and easily by virtue of the 50 fact that the relation of the racks and gears is fixed. Since the cylinder always rotates in one direction, the cooperating inking rolls do also and 55 an efficient and uniform application of ink to the plate is assured.

We are aware that the invention may be embodied in other specific forms without departing 60 from the spirit or essential attributes thereof, and we therefore desire the present embodiment to be considered in all respects as illustrative and not restrictive; reference being had to the appended claims rather than to the foregoing description to indicate the scope of the invention.

We claim:

1. A web press comprising a plate cylinder, means for reciprocating the same through a stroke substantially equivalent to a single revolution of the cylinder, an impression surface over 70 which the web is trained and in opposition to which the cylinder moves, rack and pinion means in fixed relation to the cylinder arranged to revolve it in the same direction during both phases of its reciprocatory movement, inking means co-

operating with the cylinder and means to separate cylinder and impression surface during one phase of the reciprocation of the former.

2. A web press comprising a plate cylinder, 5 means for reciprocating the same to move its axis back and forth along the same path through a stroke substantially equivalent to a single revolution of the cylinder, an impression surface over which the web is trained and in opposition to which the cylinder moves, means for moving said 10 surface away from the cylinder during one phase of the reciprocation of the latter, means to revolve the cylinder in the same direction during both phases of its reciprocating movement and inking means cooperating with the cylinder. 15

3. A web press comprising a plate cylinder, means for reciprocating the same to move its axis back and forth along the same path through a stroke substantially equivalent to a single revolution of the cylinder, an impression surface over 20 which the web is trained and in opposition to which the cylinder moves, means for moving said surface away from the cylinder during one phase of the reciprocation of the latter, means to revolve the cylinder in the same direction during both 25 phases of its reciprocating movement comprising fixed racks at opposite sides of said axis, pinions in fixed meshing relation with said racks and one-way clutch devices of opposite driving effect connecting said pinions respectively to the cylinder 30 and inking means cooperating with the cylinder.

4. A press comprising a plate cylinder, means for reciprocating the same, an impression surface in opposition to which the cylinder moves, means 35 for rotating the cylinder during the phases of its reciprocation, said means operating to revolve the cylinder always in the same direction, braking means effective on the cylinder at the limits of its stroke to check revolution thereof and inking 40 means cooperating with the cylinder.

5. A press comprising a plate cylinder, means for reciprocating the same, an impression surface in opposition to which the cylinder moves, means for rotating the cylinder during the phases of its 45 reciprocation, said means operating to revolve the cylinder always in the same direction, a brake for the cylinder and means coming into cooperation with said brake as the cylinder moves to the ends of its stroke for applying said brake. 50

6. A press comprising a plate cylinder, means for reciprocating the same through a stroke equal to its circumference, means for rotating the cylinder during the phases of its reciprocation, said means operating to revolve the cylinder always in 55 the same direction, a brake for the cylinder and means timed in synchronism with the cylinder for applying the brake as the cylinder completes a revolution at the ends of its stroke.

7. A press comprising a plate cylinder, means 60 for reciprocating the same through a stroke equal to its circumference, means for rotating the cylinder during the phases of its reciprocation, said means operating to revolve the cylinder always in the same direction, a brake for the cylinder and a cam turning with the cylinder having a rise for applying the brake as the cylinder completes a revolution at the ends of its stroke.

8. A printing press having a carriage reciprocating in opposition to an impression surface, a 70 plate cylinder on the carriage, ink-applying devices on the carriage cooperating with the cylinder, an ink fountain adjacent an end of the path of travel of the cylinder, ink transfer means on the carriage, power operated means for positively 75

protracting the same therefrom to take ink from the fountain and for positively retracting the same to deliver it to said ink-applying devices.

9. A printing press having a carriage reciprocating in opposition to an impression surface, a plate cylinder on the carriage, ink-applying devices on the carriage cooperating with the cylinder, an ink fountain adjacent an end of the path of travel of the cylinder, a plate reciprocable on the carriage, means for operating the same to protract it at the end of the stroke, and ductor rolls cooperating with said plate in protracted and retracted position respectively to deliver ink therefrom to the fountain and therefrom to the ink-applying devices.

10. A printing press having a carriage reciprocating in opposition to an impression surface, rotary printing means on the carriage, ink-applying devices on the carriage cooperating with said means, ink fountains adjacent the end of the path of travel of the carriage, a plate reciprocable on the carriage, means for moving it through an odd number of strokes for each stroke of the carriage timed to protract the same at the ends of the carriage stroke into cooperation with the adjacent fountain, and means associated respectively with the fountain and with said ink-applying devices respectively to deliver ink to the plate from the fountain and from the plate to the ink-applying devices.

11. A printing press having a carriage reciprocating in opposition to an impression surface, rotary printing means on the carriage, ink-applying devices on the carriage cooperating with said means, ink fountains adjacent the end of the path of travel of the carriage, a plate reciprocable on the carriage, means for moving the same on movement of the carriage effective to protract it into cooperation with said fountain at an end of the carriage stroke, means to deliver ink from the

fountain to the protracted plate, a ductor roll on the carriage to transfer ink from the retracted plate to said ink-applying devices, and means moving with the plate for operating said ductor roll consequentially to movement of the plate. 5

12. A printing press having a carriage reciprocating in opposition to an impression surface, rotary printing means on the carriage, ink-applying devices on the carriage cooperating with said means, ink fountains adjacent the end of the path of travel of the carriage, a plate reciprocable on the carriage, means for moving the same on movement of the carriage effective to protract it into cooperation with said fountain at an end of the carriage stroke, means to deliver ink from the 15 fountain to the protracted plate, a ductor roll on the carriage to transfer ink from the retracted plate to said ink-applying devices, and a vibrating distributor roll cooperating with said plate as it moves between its protracted and retracted positions.

13. A printing press having a carriage reciprocating in opposition to an impression surface, rotary printing means on the carriage, ink-applying devices on the carriage cooperating with said 25 means, ink fountains adjacent the end of the path of travel of the carriage, a plate reciprocable on the carriage, means for moving the same through a plurality of strokes on each stroke of the carriage, which means is effective to protract it into 30 cooperation with said fountain at an end of the carriage stroke, means to deliver ink from the fountain to the protracted plate, a ductor roll on the carriage to transfer ink from the retracted plate to said ink-applying devices, and a vibrating 35 distributor roll cooperating with said plate as it moves between its protracted and retracted positions.

CHARLES A. MEISEL.

GEORGE R. WILLIAMS.
